COMBUSTION APPARATUS

Louis H. Abel, East Cleveland, Ohio, assignor to
 The Locomotive Hollow Arch Co., Cleveland,
 Ohio, a corporation of Ohio

Application May 8, 1942, Serial No. 442,176

7 Claims. (Cl. 110—61)

This invention relates to combustion apparatus and particularly to such apparatus as is used in conjunction with boilers where large quantities of heat must be produced for the generation of steam or the like.

An object of the invention is to provide an improved apparatus which will obtain very efficient combustion of fuel.

Another object is to provide an improved combustion apparatus which will be rugged and durable in construction.

Another object is to provide an improved combustion apparatus which will be able to resist motion, jarring and the like effectively.

Another object is to provide an improved combustion apparatus which may be easily manufactured.

Another object is to provide an improved combustion apparatus which may be readily installed.

Another object is to provide an improved combustion apparatus which may be easily repaired or replaced.

Another object is to provide an improved combustion apparatus which will supply air in quantities and under conditions obtaining maximum efficiency of combustion.

Another object is to provide an improved combustion apparatus in which the supply of air to various parts may be readily controlled.

Another object is to provide an improved combustion apparatus which will be extremely durable under severe temperature conditions.

Other objects will hereinafter appear.

The invention will be better understood from the description of one practical embodiment thereof, illustrated in the accompanying drawings, showing an application of the invention to the fire-box of a locomotive boiler and in which:

Figure 1 is a central sectional view of a locomotive fire box having an arch embodying the invention;

Figure 2 is a transverse fragmentary sectional view taken on the line II—II of Figure 1;

Figure 3 is a fragmentary sectional view taken on the line III—III of Figure 1; and

Figure 4 is a fragmentary plane view taken on the line IV—IV of Figure 1.

In the drawings is shown, fragmentarily, the portion of a locomotive boiler including the fire box thereof, the other portions of the boiler and locomotive being of conventional or any desired construction.

The fire box includes a grate 1 upon which coal 2 or other fuel is burned, and is enclosed by a

5 crown sheet 3, a flue sheet 4, an inner back sheet 5, and inner side sheets 6 and 7.

5 Fire tubes or flues 8 extend forwardly from the flue sheet to the forward end of the boiler for the conducting of the heated products of combustion to the stack (not shown).

The sheets above described constitute the inner walls of a water and steam jacket including the top sheet 9, outside back sheet 10, and outside side sheets 11 and 12, a fire door 13 being provided through the inner and outside back sheets as is customary in this type of construction.

Water tubes 13, 14, 15, and 16 or thermosiphons extend downwardly from the back or 15 crown sheet to the space defined by the inside and outside throat sheets (17 and 18, respectively), and these are utilized as a support for the arch structure about to be described.

The parts above mentioned are illustrated as of 20 generally accepted type, while those to be subsequently described provide a novel means of controlling and improving combustion, both of the solid fuel 2 carried upon the grate bars 1, and of the mixed gaseous and finely divided solid 25 products of combustion which arise from the bed of solid fuel.

Rising from the innermost end of the grate is a 30 substantially vertical wall extending entirely across the space between the inside side plates and composed of several courses of hollow blocks 19, 20, and 21, preferably of a refractory material, such as fire brick.

The lowermost course 19 rests upon a metal 35 support or sill 22 which will be more particularly described later.

These blocks have upwardly extending passages 23, the lowermost ends of which continue through the sill and are open to the outside atmosphere beneath the grate bars.

40 The admission of air to the passages 23 may be controlled by a damper 24, hinged to the bottom of the sill, and having a lever 25 which may be moved from the cab by a rod 26 and handle lever 27.

Formed inwardly of the passages 23, the sill is 45 formed with a hollow recess 28 which terminates at a series of apertures 29 which open inwardly immediately above the upper surface of the fuel bed.

This hollow, like the passages previously described, has its lower end or intake opening below the surface of the grates, and the admission of air to it is controlled by a damper 30. A lever 31, rod 32, and handle lever 33 make it possible to adjust this damper from the cab.

While both dampers are shown as manually controlled by levers in the cab of the locomotive, it will be understood that any desired automatic or mechanical control may be provided.

The blocks 19, 20, and 21 constituting the vertical part of the wall are preferably arranged in vertical rows corresponding to the number of spaces between the various water tubes and between these tubes and the inner side sheets, so that in a construction such as illustrated, having four water tubes, there would be five spaces and five vertical rows of blocks.

One block 20 of each row is provided with an opening 34 through its innermost side and interior of this opening is an upwardly extending plate or deflector 35 which, in practice, projects about one-third of the way across the vertical passage 23 within the block and extends upwardly at least as far as the upper end of the aperture 34.

Extending from the top of the vertical wall in the general direction of, and supported by, the water tubes, are a series of inclined blocks 36 and 37, these being upwardly arched on their lowermost surfaces (at 38) and also on their upper surfaces (at 39) between which surfaces they have formed to define passages 40 constituting continuations of the vertical passages in the first described series of blocks.

The inclined series of blocks terminate in 30 spaced discharge heads 41, each having a generally horizontal extension 42 projecting in the direction of the flue sheet and each provided with a number of fan-like outlets 43.

At the juncture between the vertical series of blocks and the inclined series the row of blocks 21 are somewhat elbow-like.

Each block 36, of the first course of inclined blocks, is provided with an upwardly extending portion 44 having an internal passage 45 communicating with the passage within the vertical series of blocks and provided with a perforated cap 46 having generally vertically directed diverging discharge openings 47.

The interior of the blocks 36 and 37 may have formed thereon a helical rib 48, or a separate helical vane may be inserted if desired, to impart a twisting motion to the gases as they arise through the openings 40, bringing more of these gases into contact with the surface of the walls and contributing to greater heat transfer to these gases.

The operation of the device is as follows: With the fire built upon the grate, air is admitted through the recess 28 and apertures 29 immediately above the end of the fire bed at a point where combustion is particularly incomplete in present types of locomotives.

This air creates turbulence as indicated by the arrows at A and so expedites combustion of the gaseous products above the fuel bed, as well as of the solid fuel upon its inner end, not only to generate more heat, but also to prevent coking and clinkering of the fuel at this point, and thus facilitating the firing of the boiler.

Simultaneously, air rises through the vertical and inclined passages 23 and 40 within the blocks, being highly heated on its travel therethrough, so that when it emerges from the ends of these passages, its temperature is such as to cause ignition of any unburned products carried by the gases passing over the wall.

Part of this air is discharged horizontally at the outlet jets 43 in divergent directions, creating more turbulence (as indicated by the arrows

5 B) and mixing the highly preheated air with the unburned products of combustion, insuring their rapid oxidization and rapid generation of heat before these products reach the end of the flues.

10 Closely adjacent the wall, and in the space between this wall and the lower part of the flue plate, the burning products are agitated into a considerable state of turbulence (at C) by pre-heated air emanating from the jet 47 of the caps 46.

15 The eddys formed at B and C react upon each other to extend the effect of the turbulence up and down as indicated, throughout the height of the flue plate.

20 The air passing up through the passages 23 within the blocks 20 draws with it a small amount of products of combustion through the apertures 34, these products completing their combustion within the hollow of the arch and serving more highly to preheat the air which is traveling through these passages.

25 Thus it will be seen that additional turbulence and additional mixture of highly preheated air occurs at three additional places along the path of the products of combustion: one, at A, above the innermost end of the fuel bed; two, at B, adjacent the top of the arch; and three, at C, adjacent the lowermost part of the flue sheet.

30 This eliminates any substantial space in which partially burned products may collect, but insures initiation of combustion all along their path as well as an adequate supply of air of carrying on complete oxidation.

35 More complete combustion, of course, increases the efficiency by rendering all possible heat available for useful work, and reduces the quantity of smoke. The additional supply of air adjacent the solid fuel bed reduces the formation of clinkers, and thus contributes to ease of firing.

40 While I have described the illustrated embodiment of my invention in some particularity, obviously many others will readily occur to those skilled in this art, and I do not therefore limit myself to the precise details shown and described herein, but claim as my invention all embodiments, variations and modifications coming within the scope of the appended claims.

I claim:

1. Combustion apparatus comprising a combustion chamber defined by side and end walls, a top and a grate, outlet conduit means extending from one of said end walls, a baffle wall in the combustion chamber extending upwardly adjacent the last mentioned end wall and then inclined upwardly and inwardly to overlie part of the grate, the baffle wall having internal passages extending upwardly and terminating in discharge openings at the top of the wall, there being ports through the lower part of the baffle wall from said passages to the side of the wall adjacent and above the normal level of the bed of fuel upon the grate and substantially below the inclined portion of the wall, and an upwardly directed deflector within the passages extending across the inner ends 55 of said ports.

2. Combustion apparatus comprising a combustion chamber defined by side and end walls, a top and a grate, outlet conduit means extending from one of said end walls, a baffle wall in the combustion chamber extending upwardly adjacent the last mentioned end wall and then inclined upwardly and inwardly to overlie part of the grate, the baffle wall having internal passages extending upwardly and terminating in discharge openings 60 at the top of the wall, there being ports through

the lower part of the baffle wall from said passages to the side of the wall adjacent and above the normal level of the bed of fuel upon the grate and substantially below the inclined portion of the wall, and helically disposed projections within the passages, whereby gases traveling within the passages are caused to follow helical paths.

3. The combination with a locomotive boiler comprising a combustion chamber defined by a grate, a rear sheet, a crown sheet, a flue sheet, a throat sheet, and two side sheets, there being flues from the flue sheet communicating with an outlet for the gaseous products of combustion, and including inclined water tubes, of an arch comprising a series of blocks extending upwardly from between the grate and the throat sheet, a second series of blocks supported by said water tubes and extending from the top of said first series of blocks upwardly and toward the rear sheet, both series of blocks having internal passages therethrough intercommunicating to form continuous passages from beneath the grate to adjacent the top of the arch, the uppermost blocks of the second series having diverging generally horizontally disposed discharge passages directed in general toward the flue sheet and the blocks at the juncture of the two series having upwardly disposed diverging openings positioned below said first mentioned openings and between them and the flue sheet.

4. The combination with a locomotive boiler comprising a combustion chamber defined by a grate, a rear sheet, a crown sheet, a flue sheet, a throat sheet, and two side sheets, there being flues from the flue sheet communicating with an outlet for the gaseous products of combustion, and including inclined water tubes, of an arch comprising a series of blocks extending upwardly from between the grate and the throat sheet, a second series of blocks supported by said water tubes and extending from the top of said first series of blocks upwardly and toward the rear sheet, both series of blocks having internal passages therethrough intercommunicating to form continuous passages from beneath the grate to adjacent the top of the arch, the uppermost blocks of the second series having diverging generally horizontally disposed discharge passages directed in general toward the flue sheet and the blocks at the juncture of the two series having upwardly disposed diverging openings positioned below said first mentioned openings and between them and the flue sheet, there being apertures between the passages in the first mentioned series of blocks on the side toward the rear sheet.

5. The combination with a locomotive boiler comprising a combustion chamber defined by a grate, a rear sheet, a crown sheet, a flue sheet, a throat sheet, and two side sheets, there being flues from the flue sheet communicating with an outlet for the gaseous products of combustion, and including inclined water tubes, of an arch comprising a series of blocks extending upwardly from between the grate and the throat sheet, a second series of blocks supported by said water tubes and extending from the top of said first series of blocks upwardly and toward the rear sheet, both series of blocks having internal passages therethrough intercommunicating to form continuous passages from beneath the grate to adjacent the top of the arch, the uppermost blocks of the second series having diverging generally horizontally disposed discharge passages directed

in general toward the flue sheet and the blocks at the juncture of the two series having generally vertically disposed diverging openings positioned below said first mentioned openings and between them and the flue sheet, there being apertures between the passages in the first mentioned series of blocks on the side toward the rear sheet, and deflectors within the passages overlying the ends of said apertures.

6. The combination with a locomotive boiler comprising a combustion chamber defined by a grate, a rear sheet, a crown sheet, a flue sheet, a throat sheet, and two side sheets, there being flues from the flue sheet communicating with an outlet for the gaseous products of combustion, and including inclined water tubes, of an arch comprising a series of blocks extending upwardly from between the grate and the throat sheet, a second series of blocks supported by said water tubes and extending from the top of said first series of blocks upwardly and toward the rear sheet, both series of blocks having internal passages therethrough intercommunicating to form continuous passages from beneath the grate to adjacent the top of the arch, the uppermost blocks of the second series having diverging generally horizontally disposed discharge passages directed in general toward the flue sheet and the blocks at the juncture of the two series having generally vertically disposed diverging openings positioned below said first mentioned openings and between them and the flue sheet, there being apertures between the passages in the first mentioned series of blocks on the side toward the rear sheet, deflectors within the passages overlying the ends of said apertures, and passages from the space below the grate having discharge openings closely above the top of the grate directed toward the rear sheet.

7. The combination with a locomotive boiler comprising a combustion chamber defined by a grate, a rear sheet, a crown sheet, a flue sheet, a throat sheet, and two side sheets, there being flues from the flue sheet communicating with an outlet for the gaseous products of combustion, and including inclined water tubes, of an arch comprising a series of blocks extending upwardly from between the grate and the throat sheet, a second series of blocks supported by said water tubes and extending from the top of said first series of blocks upwardly and toward the rear sheet, both series of blocks having internal passages therethrough intercommunicating to form continuous passages from beneath the grate to adjacent the top of the arch, the uppermost blocks of the second series having diverging generally horizontally disposed discharge passages directed in general toward the flue sheet and the blocks at the juncture of the two series having generally vertically disposed diverging openings positioned below said first mentioned openings and between them and the flue sheet, there being apertures between the passages in the first mentioned series of blocks on the side toward the rear sheet, deflectors within the passages overlying the ends of said apertures, passages from the space below the grate having discharge openings closely above the top of the grate directed toward the rear sheet, and control means at the inlets to both series of passages.

LOUIS H. ABEL.
